UNITED STATES PATENT OFFICE

JAMES FIDDES, OF ABERDEEN, SCOTLAND
RECORDING MEANS FOR ELECTROMOTORS

Application filed October 28, 1927, Serial No. 229,329, and in Great Britain November 5, 1926.

This invention relates particularly to electric motors which are connected to and driving machines, and has for its object the provision of means for registering the work done by a machine or machines driven by an electric driving motor and for registering at the motor, the machines, or elsewhere either or all of the following:—

- A. The time during which the motor has been running without load.
  - B. The time during which the motor has been running with load.
  - C. The time during which the motor has been running overloaded.
- Such registering means may also register the number of times the motor has been on and off or has been overloaded during any particular period of time.

The present invention provides an arrangement in which the flow of current through the electric motor driving the machine is utilized to secure a correct register of the time during which either the motor or the machine with which it is associated or both have been standing idle, running idle, doing productive work, or, if desired, of the number of times the motor has been on and off, on and off load, or overloaded.

In accordance with the invention there is provided in association with the motor or motors an electro-magnet or electro-magnets or solenoid or solenoids or the like controlled by the strength of the current flowing through the driving motor or motors, and in turn controlling one or more registering devices.

The invention is illustrated in the accompanying drawings in which Fig. 1 is a perspective view of an electro-magnetically controlled instrument connected to a single recording instrument. Fig. 2 shows diagrammatically an assembly of the registering means, starter, electric motor and the machine the record of which is sought, employing two registering instruments. Fig. 3 shows an instrument including a solenoid controlling two registering instruments.

Fig. 4 shows an electro-magnetically controlled instrument similar to that shown in Figs. 1 and 2 used in conjunction with and to

control through solenoids two or more registering instruments. Figs. 5 and 5a show diagrammatically an arrangement by which a number of different records can be obtained from a single registering instrument. 55

The instrument shown in Figs. 1 and 2 comprises an electro-magnet including pole shoes 1, 1a a winding 2 and an armature 3 carried by a bell-crank lever 4, fulcrumed at 5 on the pole shoe 1, the armature 3 being balanced by a balance weight 6 adjustably mounted on the bell-crank lever and the position of the armature with reference to the pole shoes being adjustable by means of an adjusting screw 7 in screw-threaded engagement with the bell-crank lever 4 and abutting against the pole shoe 1. 60

Connected with the armature 3 by means of a rod 8 is a registering instrument including a clock generally indicated at 9. The balance or other wheel or main-spring of the clock is fitted with a suitable brake which normally prevents operation of the clock. The brake-operating mechanism is so connected to the rod 8, that, when the armature is attracted towards the pole shoes, the brake is released and operation of the clock and associated registering mechanism is permitted. The coil of the electro-magnet is wound with a gauge of wire capable of carrying the full ampere current flowing through a motor with which it is associated when the latter is on full load or overloaded, the number of ampere turns being arranged so that the pole shoes of the magnet attract the balanced arm over a small gap when the minimum ampere current required to run the said motor on no load is flowing; or the magnet may be arranged so that it will not operate until the minimum ampere current required by the motor when loaded is flowing, or only when the ampere current required by the motor when overloaded is flowing. 70

Alternatively, the magnet may be arranged in a shunt circuit and the coil in such case will be wound with a gauge of wire capable of carrying the shunted proportion of the maximum current flowing through the motor. It will be seen that, when the instrument is suitably adjusted and the flow of ampere current reaches the mini- 75 80 85 90 95 100

mum, the clockwork and the registering mechanism continue to operate during the whole time that the prearranged minimum current is flowing. Immediately the flow of electric current falls below the predetermined minimum required to attract the armature, the armature falls and thus actuates the brake whereby to arrest the clockwork and to maintain the clockwork inoperative until the commencement of the flow of the predetermined ampere current.

It will be appreciated that the number of electromagnetic devices required with this arrangement depends on the number of different registers required, one electro-magnet being required for each register. Thus in the arrangement shown in Fig. 2 two electromagnetic devices are provided, one permitting of a register of the total time the motor is running without load, and the other permitting of a register of the time it is running on load, the latter device being arranged to operate only when a load is on the motor.

It will be obvious that the electro-magnetic devices may be arranged so that one only registers when a load is on the motor and one when the latter is overloaded and that an electro-magnetic device additional to the others may be added for the purpose of registering the number of contacts made.

Fig. 3 shows a single electro-magnet or solenoid controlling two or more registering instruments.

In the instrument shown in that figure the moving armature or core 10 is balanced by means of a balance weight 11 carried by a lever pivoted at 12. The core 10 is provided at its lower end with an attachment consisting of spaced arms 13, 13' and 14 which on movement of the armature or core 10 to different extents dependent on the current passing through the electro-magnet or solenoid release the braking mechanism of one registering instrument or clock 9 and on further movement release the braking mechanism of the second registering instrument or clock, at the same time braking the first mentioned registering instrument.

The arm 14 co-operates with pivoted braking means indicated at 15 for the second clock 9a such pivoted braking means being counter-balanced by a weight or spring 16 which is movable by the arm 14. This arrangement operates as follows:—The armature or core 10 in rising first releases the brake attached to arm 13' from the flywheel arbor or spring of one registering instrument or clock 9, and on further movement causes arm 14 to raise the pivoted braking means 15 so as to release the second registering instrument or clock 9a. At the same time the arm 13 moves into position to brake the first-mentioned registering instrument or clock 9.

The distance between arm 14 and the pivoted braking means 15 is less than that between arm 13 and the flywheel arbor or spring of the first registering instrument 9, so that the first upward movement of core 10 only raises the arm 13' clear of the flywheel arbor or spring of the first registering instrument, and brings arm 14 close to the braking means 15 without operating it and also brings arm 13 nearer to the flywheel arbor or spring of the first registering instrument. Further movement upwards of the armature or core 10 causes arm 14 to release the second registering instrument 9a and brings 13 in contact with the flywheel arbor or spring of the first registering instrument 9. In this way the first registering instrument 9 will only record the actual time the motor and machine to which it is connected has been running without load, and the second registering instrument will only record the actual time the motor and machine have been running with load. The arms 13, 13', 14 may be rigid or may be semi-flexible. The armature or the attachment may have an additional arm or arms for the purpose of operating a counting or other registering instrument or instruments. 16' denotes stops fitted to the moving core 10.

The moving armature may consist of two arms connected together and operated by a pair of associated coils.

It will be obvious, also, that the electro-magnets or solenoids may be incorporated with the clockwork mechanism of the registering instrument, instead of controlling it from the outside of the casing containing the said clockwork mechanism.

In the embodiment shown in Fig. 4 there is provided a single electro-magnet 17 and solenoids 18, 19 for controlling each clock or the like. The electro-magnet 17 is in series with the motor circuit and unless shunted is wound to carry the full ampere current of the motor. The moving armature 20 of this electro-magnet 17 is provided with a contact arm 21 extending between contacts 22, 23 one of which is connected with the solenoid of the clock 9 or the like for registering the time the motor is running without load and the other of which is connected with the solenoid of the clock 9a or the like registering the time the motor is running on load. These contacts provide for completion of the circuits through the respective coils.

24 denotes the motor and starter, 25 the electric mains.

The position of the contacts 22, 23 is such that when the motor is started the contact arm 21 of the controlling electro-magnet is in contact with the contact 22 and the circuit through the solenoid 18 controlling the clock 9 registering the time the motor is running without load is closed and the brake of this clock released. When the armature 20

of the controlling electro-magnet 17 is attracted on current of a predetermined amperage passing through this electro-magnet, corresponding to a load on the motor the contact 21 is brought into contact with the second contact 23 and the circuit of the second solenoid 19 is closed and the clock 9a registering the time the motor is running on load is started.

10 Simultaneously with the closing of the latter circuit the first circuit is broken.

An arm (not shown) on the solenoid for the second clock 9a may be used to release a third clock or a counting or other registering instrument.

15 The solenoid shown in Fig. 3 and the electro-magnet shown in Fig. 4 may be wired with the full gauge of wire capable of carrying the full ampere current flowing 20 through the motor, or if shunted, the full shunted proportion.

The electromagnet 17 shown in Fig. 4 may be dispensed with if or when desired by arranging that the contacts 21 are connected 25 directly to the moving arm of an ammeter or to an additional arm fitted to the latter.

Where it is preferred that the whole of the registering parts of the instruments for a large number of motors shall be placed together in a compact and convenient form at some distant point one or more continuously moving cylinders operated by clockwork mechanism may be used to operate a series of spools providing registers for all the 30 motors.

35 When this method is adopted the magnets already referred to when operated at the pre-arranged minimum strength required to attract their respective armatures, bring their respective spools carrying registering strips or paper into contact with one of these continuously moving cylinders, each spool, of course, only remaining in contact with a cylinder when current is flowing through the motor to which it is connected 40 45 equal to the predetermined strength required to attract the armature of its controlling magnet.

Such an arrangement is shown in Figs. 5 and 5a in which 27 indicates one of a series of 50 electro-magnet disposed suitably side by side each controlling an armature 28 mounted on a pivoted lever 29 counter-balanced by a weight 30 and carrying at one end a drum 31 wound with a strip of paper and movable 55 into engagement with the periphery of a continuously rotating drum or clock 32 when the respective armature 28 is attracted to its electro-magnet 27 by current passing through the motor to which it is connected. When 60 the drum 31 comes into contact with the continuously revolving drum 32 it is caused to rotate and the paper strip carried thereby is unwound, the length of strip unwound giving a register of the time the armature is 65 attracted. The drums 31 may be merely

clock dials which turn when in contact with the drum 32 and by their position provide a register of the time during which the particular armature associated with that clock dial has been attracted.

70 Two or more electro-magnets may be associated with each motor one such electro-magnet being set for instance to ensure engagement of its drum 31 with the drum 32 when the motor is running without load and one to operate when the motor is on load or is overloaded.

I claim:—

1. Apparatus for registering the working-time of machinery driven by an electric motor, comprising an electromagnet in series with the motor circuit and energized by the energization of the motor, a paramagnetic member therefor, settable to be attracted at different loads on the machinery, a registering device, mechanical connection-means between said paramagnetic member and the balance-wheel of the registering device, and balancing means on the paramagnetic member whereby when the current pulled through the electromagnet by the driving motor attains a predetermined value, set up by the gap between the paramagnetic member and the electromagnet, the paramagnetic member is attracted to cause the registering device to indicate the time during which current greater than a predetermined minimum is pulled through the electromagnet by the motor.

2. Apparatus for registering the working-time of machinery driven by an electric motor, comprising an electromagnet in series with the motor circuit and having pole shoes, a bell crank lever fulcrumed to one shoe, an armature carried thereby, said armature being balanced by a weight adjustably mounted on one end of the bell crank lever, the downward position of the armature being limited by an adjustable set screw at one end of the lever, a rod projecting from the other end of the lever, said rod having its lower end connected to a brake shoe, said brake shoe bearing against the balance wheel of a registering clock, whereby when the current greater than a predetermined minimum is pulled through said electromagnet by said motor, the brake is released and the clock registers the time the motor is running on no load, load, or overload, respectively, according to the predetermined gap between the armature and the pole shoes.

3. Apparatus for registering the working-time of machinery driven by an electric motor, comprising a solenoid having a winding in series with the motor circuit and a movable pole, said winding having a lever pivoted at one end thereof, one end of said lever being attached to said core and the other end having a counter-weight thereon, the lower end of said movable core having two

arms on one side, said arms being curved towards each other and the upper arm normally braking the main spring of a registering clock, the other side of said core having another arm thereon, a register clock associated therewith, a device for normally holding the balance wheel of said registering device stationary; the gap between said second arm and the second balance wheel being less than that between the first arm and the first balance wheel, whereby on movement of said core to different extents by the different strengths of current, the first of said arms releases the main spring of the first clock and further movement of said core causes the arm on the second side to release the braking mechanism of the second clock, braking of the first clock by the second arm of the first side occurring simultaneously.

20. 4. Apparatus for registering the working time of machinery driven by an electric motor, comprising an electromagnet in series with the motor circuit, a movable armature therefor, a contact arm extending between two contacts, two solenoids, one of said contacts being connected with one solenoid, the core of said solenoid being connected with a clock for registering the time the motor runs without load, the other of said contacts being connected with the other solenoid, the core of said second solenoid being connected with a clock for registering the time the motor is running on load.

In testimony whereof I have signed my name to this specification.

JAMES FIDDES.
